UNITED STATES PATENT OFFICE.

CARLOS N. BRUZAUD, OF NEW YORK, N. Y.

EYE-SHIELD.

1,079,287.

Specification of Letters Patent. Patented Nov. 18, 1913.

Application filed December 16, 1911. Serial No. 696,036.

To all whom it may concern:

Be it known that I, CARLOS N. BRUZAUD, a citizen of France, residing at New York, in the county of New York and State of New York, have invented new and useful Improvements in Eye-Shields, of which the following is a specification.

This invention relates to wearing apparel and more particularly to attachments therefor in the nature of eye shields.

One of the principal objects of the invention is the provision of a simple and efficient goggle or eye shield attachment which may be conveniently and readily attached to the ordinary type of cap now commonly used by motorists, hunters, yachtsmen, and so forth.

A further object of the invention is the provision of an attachment of this character wherein the goggles or eye shields may be conveniently held over the eyes or held in elevated position or beneath the vizor of the cap.

Further objects of this invention will appear as the following specific description is read in connection with the accompanying drawings, which form a part of this application, and in which:

Figure 1 is a sectional view through the cap showing the goggles or eye shields in raised position beneath the vizor. Fig. 2 is a front elevation showing the shield in lowered position and with a portion of the vizor broken away. Fig. 3 is a sectional view on the line 3—3 of Fig. 2. Fig. 4 is a sectional view on the line 4—4 of Fig. 1. Fig. 5 is a perspective view of the shield attaching member. Fig. 6 is a horizontal sectional view showing a modification.

Referring more particularly to the drawings, 1 represents an ordinary cap which is provided as is usual with a band 2 and a vizor 3. Secured to the band 2 immediately beneath the vizor is an attaching device 45 which is constructed of a single piece of metal or in any other manner desirable and consists of a base 4 having projecting laterally therefrom a plurality of apertured attaching ears 5, by which the attachment may be readily sewed, riveted, or otherwise attached to the band. Bent up from opposite sides of the base are separate arms 6 which extend in parallel relation to each other and are provided with journal holes 7 for a purpose to be hereinafter described. A longitudinal extension of the base is bent back

upon the same between the arms 6 and is then curved upwardly and outwardly to form a retaining spring 8.

The shield here shown is in the form of an ordinary automobile goggles and consists of the usual malleable frame 9 which it is, of course, understood may be bent as desired to conform the same to the face of the wearer. This frame is constructed in the usual manner with the glasses 10 therein but in this instance is provided with a transverse extension 11 preferably formed integral with the frame and being provided with lateral arms 12 which act as journals to enter the journal holes 7 in the arm 6. These journals are formed by bending a ridge in the body of the extension and in the arms 12 and then rolling the arms into circular form. The extension 11 projects sufficiently beyond the ribs which is indicated at 13 to form a lip 14 which bears directly against the spring 8 and compresses the same when the goggles or shield is raised from operative to inoperative position or vice versa. It will readily be seen that when the goggles are in lowered position, the upper outwardly curved end of the spring 8 will engage the lip and hold the goggles firmly in operative position, while when the goggles are raised to inoperative position, the lip will be arranged upon the opposite side of the pivotal center and thus be held by the springs against displacement.

In the modification shown in Fig. 6, the base 4 is provided with lateral extensions 15 having pointed ends 16. These extensions are in the nature of penetrating prongs which are adapted to pass through the band twice and be bent over the base beneath the first return of the spring, thus the attachment may be readily secured to the cap without the use of stitching, rivets, or other independent fastening devices. By pivoting the goggles in this manner to the cap, they may be either held in operative position over the eyes so as to shield the same or may be conveniently held beneath the vizor of the cap in an out-of-the-way position when not needed, thereby obviating the necessity of taking off the goggles and putting them into the pocket where they are liable to become broken or strapping them over the cap, a practice which is now commonly in vogue.

It will be clearly understood that by a slight modification, the same device may
